Application January 28, 1939, Serial No. 253,292

17 Claims. (Cl. 101—218)

In printing by the offset method there are three main drums or rolls. A blanket roll or printing drum rotates in contact with the plate roll, receives the ink therefrom and prints it on the sheet being printed, and a third roll called the platen presses the sheet against the blanket roll. For high quality printing it is of course necessary that the contacts between each pair of rolls be delicately and accurately adjusted. On the other hand, it is important that when no sheet is fed to the blanket and platen rolls for printing, these rolls should be separated so that the platen will not contact the inked portion of the blanket roll since the ink thus transferred to the platen would be printed on the backs of the sheets subsequently printed. It is also highly desirable that when no sheet is fed to the blanket roll and platen, the blanket roll and plate roll be separated so that no excess of ink will be applied to the blanket roll.

An object of the invention is to provide very simple and satisfactory means for separating the blanket roll from both the plate roll and the platen roll if no sheet is being fed to the blanket roll and platen at the proper time. This is accomplished very simply according to the present invention by so mounting the blanket roll that upon simply releasing a latch the blanket roll will move in a direction away from both the plate roll and the platen. If automatic operation is desired, it may be provided by having a feeler at the feeding position moved in synchronism with the blanket roll and automatically releasing the latch when no sheet is at the feeding position at the proper time. This system lends itself admirably to various other advantages, the projection of which may be considered additional objects of the invention.

The latching device may be connected with a control switch so that the press will be stopped automatically when the blanket roll is separated from the other rolls or "thrown out." This is desirable because with a good automatic preliminary feeder the absence of a sheet at the final feeding position probably indicates that the supply of sheets has been exhausted. The interconnection of the latch and the switch also is advantageous in that the press will automatically be started when the latch mechanism is operated to begin the return of the blanket roll to its active position. The latch may also be used for controlling the sheet counter so that, when the latch is automatically released because no sheet is being fed, the counter will cease to count.

The throw-out system can be combined with

the contact adjustment system so that neither will interfere with the other and so that some parts will be used in common. An eccentric shaft has been found very satisfactory for both purposes. It also lends itself to the use of special couplings between the gears and the rolls which permit the gears to be journaled about fixed axes so that they will always mesh properly. A universal or variable-axis coupling may therefore be provided between the driving gears and both the blanket roll and the platen roll and that of the blanket roll will serve to permit both the contact adjustments and the throw-out movement.

15 Additional advantages and objects of the invention will be apparent from the following description and from the drawings, in which:

Fig. 1 is a perspective view of a press chosen for illustration of this invention with parts broken away for the sake of clarity.

Fig. 2 is a side elevation of the structure shown in Fig. 1 with the blanket roll in thrown-out position.

Fig. 3 is a corresponding view showing the blanket roll in operative position.

Fig. 4 is a fragmentary sectional view taken approximately on the line 4—4 of Fig. 3.

Fig. 5 is a fragmentary longitudinal sectional view showing particularly the automatic control device.

Fig. 6 is a fragmentary view diagrammatically illustrating the drive for the preliminary feeder.

Fig. 7 is a fragmentary horizontal sectional view taken approximately on the line 7—7 of Fig. 2.

Figs. 8 and 9 are diagrammatic views illustrating the relations of the centers and the dispositions of the various eccentrics.

A preferred embodiment of the invention has 40 been shown in the drawings and will hereinafter be described all as required by section 4883 of the Revised Statutes, but the invention may take numerous forms.

The invention has been illustrated as embodied in an offset printing press in which the actual printing is performed by a blanket roll 11 against which the sheet is fed by a platen 12. The blanket roll 11 is covered with a smooth-surfaced blanket 13 of rubber or the like which receives the ink from a plate roll 14. Of course, suitable inking rolls, not shown, must be provided for the plate roll. It will be understood that these three main rolls or drums are geared together to rotate at the same peripheral speed 50 so that the plate roll prints onto the blanket 13

which in turn prints onto a sheet fed between the blanket roll 11 and the platen 12.

It is customary to feed the sheets to the printing rolls 11 and 12 in timed relation therewith automatically so that with each revolution of the blanket roll 11 a sheet will be inserted at the proper time for printing. This feeding mechanism may include a separating roller 16 (Fig. 5) for separating a sheet from a stack, and a conveyor 17 which delivers the sheet against stop fingers 18 but which is also laterally biased to urge the sheet against a side guide 19 to secure lateral registry thereof. The stop fingers 18 comprise a portion of the final feeding and registering mechanism, which also includes the feed rollers 21, the pressure roller 22 and the mechanism for operating these devices.

Although any feeding mechanism might be used with the present invention, an understanding of the feeding mechanism may help in obtaining an understanding of the present invention. The separating roller 16 is driven intermittently by a reciprocating rack 26 (Fig. 6) and pinion 27 by which the roller 16 is driven through an overrunning clutch represented by the rollers 28. The rack 26 reciprocates for each revolution of the blanket roll 11, being driven, as illustrated diagrammatically in Fig. 6, by means eccentrically connected to some member 29 rotating in unison with the blanket roll. The separating roller 16 feeds a sheet to the conveyor 17 on which it is gripped by a pressure roller 31 and fed against the stop fingers 18 and the side guide 19. While the stop fingers 18 and feed rollers 21 are stationary and while the sheet is at rest against the stop fingers 18, the pressure roller 22 is lowered by action of cam 32 so that the sheet is firmly gripped between the pressure roller 22 and the feed rollers 21. Immediately thereafter, cam 33 operates gear segment 34 to rotate feed roller 21 to feed the sheet to the bite between blanket roll 11 and the platen 12. The shape of the cam 33 is such that at the time the sheet reaches the bite it is moving at the peripheral speed of these printing rolls. Immediately thereafter, the pressure roller 22 is released by cam 32 so that the sheet may be drawn freely through the feeding mechanism. The cycle is completed by a return of the feed roller 21 and fingers 18 to their initial position under influence of the return spring 36, which incidentally eliminates all slack or play from the drive of the feed roller 21 so that the feeding of the sheet is absolutely uniform.

Whenever the stack of sheets runs out and perhaps on rare other occasions due to some failure of the mechanism, there will be no sheet on the final feeding table 37 to be fed by the roller 21 to the printing rolls 11 and 12. If these rolls are permitted to rotate in contact with one another when no sheet is fed thereto, the ink from the blanket 13 will be printed on the platen 12. It is obvious that this is very undesirable, one reason being that the ink on the platen 12 would be printed on the reverse side of the next sheets fed with the result that such sheets would be ruined. It has been common heretofore to provide means for separating the two printing rolls corresponding to the blank roll 11 and the platen 12. This separation is called a "throw-out." Sometimes the expression "platen throw-out" is used because originally the platen was the roll which was moved.

In the present instance the blanket roll 11 is moved and therefore the expressions "blanket roll throw-out" and "impression roll throw-out" would be more appropriate. The term 5 "printing roll throw-out" could be used to describe the movement of either of the rolls.

It is highly desirable to accomplish the throw-out by means of moving the blanket roll 11 in a direction away from both the platen 12 and the plate roll 14. The reason is that this throw-out will separate the blanket roll 11 from both of these other rolls so that if printing is promptly resumed the blanket roll 11 will be in condition to print properly immediately. If it 10 were left in contact with the plate roll 14 while the press rotated without supplying sheets to be printed, the plate roll 14 would transfer an excess of ink to the blanket 13 and hence the initial subsequent printing would be unsatisfactory.

Throw-out mechanism

Complicated mechanisms have been provided heretofore for causing the blanket roll 11 to move away from both rolls 12 and 14. According 25 to the present invention this is accomplished very simply. As shown roughly in Fig. 1, the blanket roll 11 rotates on a shaft portion 41 which forms an eccentric part of shaft 42 journaled in the press frame 43. The shaft 42 may be provided with a handle 44 by which the shaft 42 may be turned with the result that its eccentric portion 41 will move the blanket roll 11 toward or from the platen 12 and plate roll 14. This eccentric mounting is seen 30 best in Fig. 4 and is described in detail subsequently.

The shaft 42 also carries a lever 46 which may be called a latch lever or a throw-out lever. When the blanket roll 11 is in its thrown-out position as 40 seen in Fig. 2, the latch lever 46 is not latched but is held in this position by a throw-out spring 47 which urges the lever 46 against a stop 48 preferably having a rubber collar 49 for absorbing shock as the lever 46 is slammed against it. 45 When the press is to be operated, the handle 44 is turned in a counterclockwise direction until the latch lever 46 is caught in front of a ratchet-shaped lug 51 on a pivoted latch arm 52 which is urged upwardly by a spring 53. With the parts 50 in this position, as shown in full lines in Fig. 3, the blanket roll 11 will be in contact with the plate roll 14 and the platen 12 or, in other words, the press will be in operative condition.

Whenever there is no sheet in position to be 55 fed to the printing rolls 11 and 12, a throw-out may be accomplished with extreme ease and rapidity merely by thrusting the latch arm 52 downwardly. For this purpose a handle 54 is provided thereon. As soon as the latch arm 52 is 60 pivoted downwardly enough to permit the latch lever 46 to clear the lug 51, the spring 47 will snap the lever 46 against the stop 48, thus turning shaft 42 and shifting its eccentric portion 41 to move the blanket roll 11 to the position seen 65 in Fig. 2.

Motor control

It will be observed that the latch arm 52 has been illustrated with a second ratchet-shaped lug 56 thereon. This serves a very useful purpose in that it aids the latch lever 46 to control a switch 57 for starting and stopping the press. When the latch lever 46 is first moved to be engaged by the lug 56, it starts the motor and not until its final movement to the lug 51 is the

blanket roll 11 brought in contact with the platen 12 and plate roll 14. The latch lever 46 is connected with the motor switch 57 by means of a rod 58 and a bell crank 59 which it operates through a coupler 60 swiveled to the bell crank. The bell crank 59 has a slotted engagement with the toggle lever 61 of the switch 57. In Fig. 2 toggle lever 61 has been shown in the "off" position. It is thrown to the "on" position of Fig. 3 by action of a spring 62 bearing at one end against a pin 63 carried by rod 58 and at the other end against the coupler 60. The rod 58 extends through the coupler 60 and is slidable with respect thereto so as to leave the rod 58 free to move after the toggle 61 has reached the limit of its movement. Thus, as the latch lever 46 is moved to the intermediate position in engagement with the lug 56, the rod 58 and the spring 62 turn the bell crank lever 59 to snap the toggle 61 to turn on the motor and start the press. When the press has obtained the proper speed, the latch lever 46 is turned further to engage the lug 51. This in turn moves the rod 58 further but, since the bell crank 59 cannot turn further, the rod 58 slides in coupler 60, thus merely compressing the spring 62. A cotter pin 66 is secured in the end portion of the rod 58 so that when the latch arm 52 is released and the latch lever 46 is sprung back to the position shown in Fig. 2, the cotter pin 66 (or a washer) will engage the coupler 60 of the bell crank 59 and rotate this lever to shift the toggle back to the "off" position shown in Fig. 2.

Automatic throw-out

It will be observed that the throw-out and motor control mechanism described to this point are independent of the feeding mechanism and could even be used when the sheets are fed mainly by hand. In this form the throw-out mechanism is very simple and economical to manufacture although it is entirely manually operated. When cost considerations will permit, an automatic throw-out operation is very desirable, and, since the illustrated form of throw-out mechanism lends itself admirably to automatic operation, a structure for providing such automatic operation has been illustrated.

The latch arm 52 may be mounted on a shaft 71 on which in turn may be mounted a release arm 72 having a lug 73 positioned just below the top of feeding table 37 which is provided with a slot 74 to expose the lug 73 therethrough. When no sheet is in place it will be possible for a feeler 75 to pass into the slot 74 and engage the lug 73. The feeler 75 is reciprocated in timed relation with the blanket roll 11 so that it moves forwardly just as the printing of one sheet is finished and another sheet should be in the feeding position. If the sheet is there, the feeler 75 will be held up above the table 37 out of contact with the release arm 72. If no sheet is present, the feeler 75 will dip into the slot 74, engage the lug 73 and operate the release arm 72 and the latch arm 52 to release the lever 46 so that the spring 47 will sap the latch lever 46 against the stop 48, thus throwing out the blanket roll 11.

Although the feeler 75 may be reciprocated in any suitable manner, it has been illustrated as operated by the cam 33 which also operates the feed roller 21. This operation is by means of a link 76 swiveled to and connected between the arm 77 and a crank arm 78 mounted on shaft 79 which carries another crank arm 80 to which the

feeler 75 is pivoted. A special return spring may be provided or spring 36 may be relied upon.

Adjustment of printing rolls

- 5 Although the foregoing structure may be used with a variety of forms of mounting and adjustment means for the printing rolls, it lends itself admirably to the simplified and extremely convenient structure shown in Fig. 4.
- 10 There are two adjustments necessary between every pair of printing rolls. One is the adjustment for uniformity of pressure along the line of contact and the other is the adjustment for the amount of pressure. The adjustment for uniformity of pressure is a relatively fixed adjustment and is necessary usually to compensate for inevitable inaccuracies in the manufacture of the press. According to the present invention the uniformity of pressure is produced by eccentric bushings which shift one end of each shaft on which a roll to be adjusted is mounted. In the case of the blanket roll 11 this shaft is the shaft 42. This shaft 42 is provided with a stub extension 83 which is journaled in an eccentric bushing 84 (Figs. 4, 8 and 9) which is rotatably carried by the press frame 43. In other words, the rotatable bushing 84 is provided with an eccentric hole in which the stub 83 of the shaft 42 is journaled. The bushing 84 is preferably provided with a lever 86 which permits rotation of the bushing to shift the stub shaft 83. The press is designed so as to have the bushing 84 initially at such angular position that its rotation will move the stub shaft 83 either directly toward or directly from the plate roll 14. This positioning is seen best in Figs. 8 and 9, in which it is seen that line A—B from the center A of bushing 84 to center B of stub shaft 83 is perpendicular to the line B—C, C being the axis of plate roll 14. Thus, if the pressure of the plate roll 14 at the side of the blanket roll 11 near the lever 86 is lighter than at the other side, the lever 86 and its bushing 84 will be turned in a direction to move the stub shaft 83 toward the plate roll 14 and increase the pressure at this side. When an adjustment providing uniform pressure has been obtained, a screw 88 passing through a concentric slot 89 in lever 86 may be tightened to lock the bushing 84 in this adjusted position. The lever 86 may have a handle 90.
- 15 In order to align the platen 12 with blanket roll 11 so as to provide uniform pressure along their line of contact, a bushing 91 similar to the bushing 84 may be provided. In this bushing is journaled a shaft 92 on which the platen 12 rotates, the journaled portion of the shaft 92 being eccentrically positioned in the bushing 91 as was the case of the stub shaft 83 in the bushing 84. A handle 93 is preferably provided for turning the bushing 91 so as to provide uniform pressure along the line of contact between the platen 12 and the blanket roll 11. When this uniform pressure has been attained, a screw 94 may be tightened to maintain the adjustment.
- 20 65 It will be noted that at the other end of each of printing rolls 11 and 12 additional eccentric bushings 96 and 97 are provided. These bushings need not be adjustable, however, and are illustrated as permanently secured in one position by screws 98. The shafts 42 and 92 could be journaled directly in the frame 43 in lieu of bushings 96 and 97, but the provision of the bushings 96 and 97 is more convenient and supports the shafts better.
- 25 70 The amount of pressure between the blanket

roll 11 and the plate roll 14 may be adjusted by turning the shaft 42. In other words, the same means is used for the throw-out as for the pressure adjustment. It will be observed that the pressure between these two rolls depends upon the position of the shaft 42 at the time that the latch lever 46 is in its final position in engagement with the lug 51. This position may be adjusted by loosening screws 101 which extend through slots 102 in the latch lever 46 and screw into plate 103 having a hub 104 keyed to shaft 42. When latch lever 46 is in its latched position and the screws 101 loosened, the handle 64 may be turned to adjust the pressure between blanket roll 11 and plate roll 14, after which the screws 101 may be tightened. Thereafter, every time the latch lever 46 is moved to its final latching position, the same contact pressure will be obtained, assuming uniform plate thickness on the plate roll 14. Of course, when the plate roll 14 is changed, readjustment of the pressure may be made very easily after loosening screws 101. The eccentricity of shaft 42 (line B—D) is preferably normally disposed approximately parallel with a line C—E between the axes of platen 12 and plate roll 14, so as to have a maximum component of motion away from these rolls during the first part of the throw-out.

The pressure of the platen against the blanket roll is similarly controlled. The shaft 92 is provided with eccentric bearing portions 106 similar to the eccentric bearing portion 41 of shaft 42. It is about these eccentric portions 106 that the platen 12 rotates. Likewise, the shaft 92 is preferably provided with a handle 107 so that the shaft 92 may be rotated to shift the eccentric portions 106 and hence the platen 12 toward or from the blanket roll 11. When the proper adjustment of pressure is obtained, the adjustment may be secured by tightening screw 108 which extends through a slot in the base portion of handle 107. It will be observed that this adjustment is made with extreme ease and hence can be varied quite readily if changes in the thickness of the sheets should so require. Of course, this adjustment should be made when the latch lever 46 is in its final position and after the pressure between the blanket roll 11 and plate roll 14 has been adjusted.

Inasmuch as these various adjustments move the rotational axes of the rolls toward and from one another, a problem is encountered in connection with the gearing of these rolls since gears are of course designed to be operated about axes an exact distance apart. If the gears are slightly separated, there will be excessive slack between them and if they are moved closer together there will be a tendency toward a binding effect between them. In either event, the friction and wear will be increased. According to the present invention the gears are maintained at constant axes regardless of movement of the printing rolls. This means of course that the central axis of a given printing roll will not always coincide with the axis of the gear and it is necessary to provide some means for accommodation between these two axes. According to the present invention a coupling is provided of the type known as an Oldham coupling which may be broadly described as a variable-axis coupling. According to this style of coupling, an intermediate coupling member 111 is provided between the gear 112 and the blanket roll 11 which it drives. The intermediate coupling member 111 has a sliding engagement with the gear 112 in one direction and a sliding

engagement with the blanket roll 11 in the perpendicular direction. This permits the blanket roll 11 to have a planetary movement about the axis of the gear 112 as the two rotate together.

5 The sliding relationship is accomplished by means of radial splines 114 and 116 on the gear and roll respectively, which fit in corresponding grooves in the intermediate coupling member 111. As gear 112, coupling 111 and roll 11 rotate they never depart from the constant angular relationship they would have if keyed to a single shaft.

In similar manner, an intermediate coupling member 118 is provided between the gear 119 and the platen 12, having the same engagement 15 with each of these members as does the intermediate member 111 with the gear 112 and the blanket roll 11.

It may be observed that a single bushing 120, preferably of hardened steel, may be secured to the frame 43 to serve as a bearing for both the bushing 96 and the gear 112 which may in turn have a sleeve of bearing metal for engaging the bushing 120. This positions the bushing 96 concentrically with the gear 112 so that, as seen 20 best in Fig. 9, it is out of alignment with bushing 64.

Control of counter

It is common practice with printing presses to provide a counter for counting the sheets as 30 they are printed and such a counter has been shown at 121 in Fig. 2. This counter is actuated by a counter lever 123 which is pivoted at 124 to the press frame 43. The counter lever 123 rides on cam 126 during operation of the press. 35 The cam 126 rotates with the plate roll 14 and upon every revolution thereof the low part of the cam permits spring 127 to draw the counter lever 123 down and operate the counter 121.

If the press continues to rotate after the blanket roll 11 is thrown out, it is of course desirable that the counter should not operate since it would produce a false count. To prevent the counter from operating, the latch lever 46 is provided with a hook-like extension 128 which slips 45 over a flange 129 on the idle end of the counter lever 123 thereby holding this counter lever in the position shown in Fig. 2 so that it cannot operate the counter 121 even when the low part of the cam 126 is adjacent the counter lever 123. 50 The end of the hook 128 may be beveled so that even with the counter in the position shown in Fig. 3 the hook will pass over the flange 129 if the latch arm 52 should be operated at that time to cause a throw-out. However, the relationship of cam 126 and cam 33 is such that the 55 automatic throw-out would never occur when the counter lever is in the position shown in Fig. 3.

It should be noted that hook 128 is sufficiently long so that the counter does not again come into operation until the latch lever is moved substantially to its final latched position, i. e. after it leaves the intermediate position.

Operation

In preparing the press for use, the eccentric bushing 84 is first adjusted to provide uniform contact pressure along the line of contact between the blanket roll 11 and the plate roll 14. Next, the eccentric bushing 91 is adjusted to provide uniform contact pressure along the line of contact between the platen 12 and the blanket roll 11. Of course, these adjustments should be made when the various rolls are approximately 70 in their operative positions. Next, the proper

pressure is obtained between the blanket roll 11 and the plate roll 14 by loosening the screws 101 and turning the handle 44 while the latch lever 46 is locked in operative position by the latched lug 51. The pressure of the platen 12 against the blanket roll 11 may be adjusted by turning the shaft 92 after loosening screw 108.

To start the press for a given run or after a throw-out, it is merely necessary to turn the handle 44 through two steps. In the first step the latch lever 46 latches on the lug 56. This initial movement actuates rod 58 to turn on the motor switch 57. When the desired speed has been reached, the handle 44 is turned farther to latch the latch lever 46 on lug 51. This second movement brings the blanket roll 11 into proper contact with the plate roll 14 and the platen 12 and also releases the counter lever 123 so that it will count the sheets that are printed. If at any time there is no sheet on the feed table 37 at the time the sheet should be fed to the printing rolls 11 and 12, the blanket roll 11 may be thrown out, and separated from both the platen 12 and the plate roll 14 merely by lowering the latch arm 52 for which purpose the handle 54 thereon is provided. This permits spring 47 to snap the latch lever 46 against the stop 48, thus turning the shaft 42 so that the eccentric bearing portions 41 are moved to remove the blanket roll 11 away from both of the other rolls. This throw-out movement of the lever 46 also causes the extension 128 to block further movement of the counter arm 123 and furthermore actuates the rod 58 to operate the switch 57 to the "off" position, thus stopping the press.

If the automatic control features are provided, the feeler 75 will be reciprocated once for each revolution of the blanket roll 11. Normally this will have no effect for the feeler 75 will rest on top of the sheet which is being fed. When no sheet is present, however, the feeler 75 will fall through the slot 74 and engage the lug 73 of release arm 72, thereby operating the latch arm 52 downwardly, thus producing the throw-out as described in connection with the manual operation.

From the foregoing it is seen that a printing press is provided having an extremely simple and satisfactory throw-out mechanism. No longitudinally sliding parts or guideways are required. Both the throw-out and the adjustment of the pressure of the blanket roll on the plate roll are accomplished by means of a shaft having eccentric bearing portions for the blanket roll. This same shaft is journaled eccentrically in a bearing bushing which can be rotated to adjust the uniformity of pressure of the blanket roll on the plate roll. Similar means for adjustment of pressure and uniformity of pressure are provided for the platen. In each case the bearing bushings are journaled within a bearing member which also serves as a fixed bearing for the gear driving the adjacent roll. The possible displacement of the axis of the roll and of the gear is compensated for by an Oldham coupling.

The eccentric type of throw-out mechanism lends itself admirably to the provision of a simple type of latch which may easily be controlled automatically if desired. Furthermore, the latch mechanism is preferably coupled to the motor control switch and the latch is preferably provided with two steps so that a single handle may be used first to turn on the motor by movement to the first step and then to throw the printing rolls into contact by movement of the second step. With this arrangement the operation of

the throw-out will automatically turn off the motor. The mechanism may also be coupled to the counter so that it will also stop the operation of the counter.

Although the apparatus need not be designed for disposing the eccentrics at the angular positions shown in the drawings, these positions will give the most satisfactory directions of movement, even though in the case of the blanket roll 11 this requires two different directions of movement. Thus, the throw-out movement of the blanket roll should be in a direction which moves it substantially equally away from both the plate roll and the platen roll, while for the alining adjustment the movement of one end of the blanket roll should be directly toward and from the plate roll 14. To provide the throw-out movement the apparatus is designed to place the axis B of stub shaft 83 in the position shown in Fig. 9 with respect to the axis D of the blanket roll 11. The initial movement of the center D as the shaft is rotated about the center B will be in a direction perpendicular to the line B-B. Hence, with this line parallel to the line C-E the initial movement will be approximately equally away from both of the rolls. As a matter of fact, because of the larger size of the plate roll 14 the initial movement will produce a little less separation from this roll, but because of the circular movement of the axis D the latter part of the movement will be greater with respect to the roll 14 so that the total separation is still about the same from both rolls.

Since the eccentric 84 is moved only to adjust one end of the blanket roll 11 toward or from the plate roll 14, it is desirable that this eccentric be so disposed that it will provide this movement with the least undesirable components in other directions. Hence, the eccentric bushing 84 is positioned with its axis A on a line extending through the axis B and perpendicular to the line B-C. Any movement along this line will ordinarily be extremely small and hence the fact that the path of the axis B is circular is not significant. It will be observed that because the motion of the axis B is along the line B-C this adjustment does not tilt the axis B out of its common plane with the axis C and, furthermore, it has almost no effect on the uniformity of pressure between blanket roll 11 and platen roll 12. It will be observed that if the bushing 96 were used for this adjustment, the direction which it would move the axis B would not be nearly as satisfactory because the bushing 96 is concentrically positioned with respect to the gear 112. Ordinarily such bushings as the bushings 96 and 84 would be positioned in alinement but by positioning them out of alinement and by adjusting the one which is independent of the gearing the advantageous direction of movement of the axis B, already discussed, is obtained. This misalinement of the bushings 84 and 96 is thus an expedient adopted for the purpose of providing two different directions of movement, namely the throw-out movement away from both the platen 12 and the plate roll 14 and the adjusting movement which is directly toward or away from the plate roll 14. Although the bushings 84 and 96 are misaligned when they are in the illustrated angular positions for which they are designed, their eccentric openings are alined. In other words, the machine is designed so that, except when corrective adjustment is necessary, a line extending through the eccentric extensions of

shaft 42 will be truly parallel with the axis of plate roll 14.

In connection with the platen 12 it is not necessary to resort to the misalignment of the bushings since only one direction of movement of the axis E is desired. This direction is toward or from the blanket roll 11 and hence the rotational axis F of the shaft 92 is positioned on a line extending through the point E at approximately right angles to the line D—E. For convenience, since no other direction of movement is necessary, the bushings 91 and 97 are positioned concentrically with the gear 119 which is concentric with the normal position of the platen roll 12.

In using the terms "engagement" or "contact" herein with reference to the blanket and platen rolls 11 and 12, it is of course not intended to imply that there is no sheet between them.

We claim:

1. An offset printing press including a plate roll, a blanket roll for receiving ink from the plate roll, a platen roll for pressing a sheet to be printed against the blanket roll, means for feeding successive sheets to the blanket roll to be printed; the blanket roll being movable in a direction away from both the plate roll and the platen roll so that it may be separated from both the platen roll and the plate roll by a single movement and being biased in said direction; latch means for latching the blanket roll in normal engagement with the plate roll and platen roll, means for automatically releasing the latch means, said means being ineffective if a sheet is being fed to the blanket roll at the proper time, and means for stopping the press when the blanket roll is thrown out.

2. A printing press including a printing roll rotatable on an eccentrically mounted shaft, ink-applying means for applying ink to the printing roll, a platen roll for pressing a sheet to be printed against the printing roll, and means applied to one end of the shaft only for turning said shaft; the angular disposition of the shaft being such that as it is turned in the appropriate direction the printing roll initially moves in a direction away from both the ink-applying means and the platen roll.

3. A printing press including a printing roll rotatable on an eccentrically mounted shaft, ink-applying means for applying ink to the printing roll, a platen roll for pressing a sheet to be printed against the printing roll, means applied to one end of the shaft only for turning said shaft; the angular disposition of the shaft during the printing engagement being such that an extended line between the shaft axis and eccentric center is remote from and outside of the points of contact between the printing rolls so that as the shaft is turned in the appropriate direction the printing roll moves in a direction away from both the ink-applying means and the platen roll, and latch means for securing the shaft at an angular position for holding the rolls in contact and releasable to let the shaft turn to move the rolls out of contact, said latch means including a fixed latch member and an arm for cooperating therewith secured to the shaft with angular adjustability whereby the pressure between the rolls can be predetermined by the angular adjustment of the arm on the shaft.

4. A printing press including a printing roll rotatable on an eccentrically mounted shaft, ink-applying means for applying ink to the printing roll, a platen roll for pressing a sheet to be printed against the printing roll, means for turn-

ing said shaft; the angular disposition of the shaft being such that as it is turned in the appropriate direction the printing roll moves in a direction away from both the ink-applying means and the platen roll, latch means for securing the shaft at an angular position for holding the rolls in contact and releasable to let the shaft turn to move the rolls out of contact, said latch means including a fixed latch member and an arm for cooperating therewith secured to the shaft with angular adjustability whereby the pressure between the rolls can be predetermined by the angular adjustment of the arm on the shaft, and a switch for controlling the rotation of the rolls connected to the arm to be operated thereby in the initial part of the movement of said arm in returning the movable roll to its operative position after a throw-out.

5. A printing press including two printing rolls, one of which is movable with respect to the other, a control member for moving the movable roll into contact with the other, and a motor switch for controlling the rotation of said rolls and operated to the "on" position by the control member before it moves the movable roll into contact with the other roll.

6. A printing press including two printing rolls, one of which is movable with respect to the other, throw-out means for causing the movement of the movable roll away from the other adapted to be manually reset, and a switch for controlling the rotation of the rolls operated to the "off" position by a roll-separating operation of the throw-out means and to the "on" position by a reset operation thereof.

7. A printing press including a pair of rolls adapted to rotate in contact with one another, a shaft eccentrically journaled for carrying one of the rolls, means for turning the shaft and locking it in a turned position to adjust the contact pressure between the rolls, an eccentric bushing journaling the shaft at one end thereof and turnable to adjust the uniformity of contact pressure along the line of contact between the rolls, said bushing with the shaft therein being carried on the inside of a fixed bearing member, a gear rotatably carried on the outside of said bearing member, and a variable-axis coupling connecting said gear and movable roll.

8. A printing press including a pair of rolls adapted to rotate in contact with one another, shaft means for carrying one of the rolls, a bearing for one end of the shaft means, and a pivotally mounted bushing having the other end of the shaft means eccentrically journaled therein, some point on the orbit of the center of the eccentrically journaled shaft end being in a line extending through the center of the other shaft end and substantially parallel with the axis of the other roll.

9. A printing press including a pair of rolls adapted to rotate in contact with one another, shaft means for carrying one of the rolls, a bearing for one end of the shaft means, and a pivotally mounted bushing having the other end of the shaft means eccentrically journaled therein, some point on the orbit of the center of the eccentrically journaled shaft end being in a line extending through the center of the other shaft end and substantially parallel with the axis of the other roll, this point being approximately at a point of tangency between said orbit and the line extending to said axis.

10. A printing press including two printing rolls, one of which is movable with respect to the

other, throw-out means for causing the movement of the movable roll away from the other and including a control member for resetting the rolls, and a switch for controlling the rotation of the rolls operated to the "off" position by operation of the throw-out means and operated to the "on" position by operation of the control member in its resetting movement before it moves the movable roll into printing relation with the other roll.

11. A printing press including two printing rolls, one of which is movable with respect to the other, throw-out means for causing the movement of the movable roll away from the other and including a control member for resetting the rolls, and a switch for controlling the rotation of the rolls operated to the "off" position by operation of the throw-out means and operated to the "on" position by operation of the control member in its resetting movement before it moves the movable roll into printing relation with the other roll, the throw-out means also including latch means for latching the control member in two operative positions, one corresponding to the position at which the switch is turned on, and the other corresponding to the position at which the rolls are in printing relationship.

12. A printing press including a blanket roll, a plate member and a platen member, with the blanket roll movable between two positions in one of which it engages the plate member and the platen member and in the other of which it engages neither, and a control member operable to a position at which it causes operation of the press to cease, operable to a printing position for causing the movement of the blanket roll into printing engagement with the other two members and operable to a preliminary position, before causing the blanket roll to engage either of the other members, for causing the press to operate normally in respects other than engagement between the blanket roll and said members.

13. A printing press including a blanket roll, a plate member and a platen member, with the blanket roll movable between two positions in one of which it engages the plate member and the platen member and in the other of which it engages neither, a control member operable to a position at which it causes operation of the press to cease, operable to a printing position for causing the movement of the blanket roll into printing engagement with the other two members and operable to a preliminary position, before causing the blanket roll to engage either of the other members, for causing the press to operate normally in respects other than engagement between the blanket roll and said members, and latch means effective to hold said control member in either the preliminary position or the printing position.

14. In a printing press, a printing couple including a rotating cylinder, means for feeding sheets to the couple including registration stop means against which a sheet is preliminarily fed, feed rollers for advancing the sheet from the stop means to the printing couple, means for intermittently rotating one of said rollers in timed relation to the rotation of said cylinder, a sheet detector moved in the direction of movement of the sheet during the feeding movement of the

driven feed roller adapted to be supported by the sheet if a sheet is present and adapted to drop through the intended plane of the sheet if the sheet is absent, and throw-out means controlled by the forward movement of the sheet detector if it has dropped through the intended plane of the sheet for separating the members of the printing couple.

15. In a printing press, a printing couple including a rotating cylinder, means for feeding sheets to the couple including registration stop means against which a sheet is preliminarily fed, feed rollers for advancing the sheet from the stop means to the printing couple, feed control means including cam means on the cylinder for moving one feed roller toward the other substantially without rotation of either feed roller and for thereafter driving one of the feed rollers to advance the sheet from the stop means to the printing couple, a sheet detector actuated by the same cam means and moved in the direction of movement of the sheet during the feeding movement of the driven feed roller adapted to be supported by the sheet if a sheet is present and adapted to drop through the intended plane of the sheet if the sheet is absent, and throw-out means controlled by the forward movement of the sheet detector if it has dropped through the intended plane of the sheet for separating the members of the printing couple.

16. In a printing press, a printing couple including a rotatable cylinder, a shaft supporting the cylinder for rotation about the axis of the cylinder and eccentrically journaled for a pivotal movement moving the cylinder toward or from the other member of the printing couple, a control member carried by the shaft, and means for maintaining the control member at a predetermined position to produce a predetermined pressure between the members of the printing couple; the control member being angularly adjustable on the shaft and securable in a predetermined position thereon by screw means extending through slot means in the control member and screwed home to draw the control member into rigid relationship with the shaft.

17. In a printing press, a printing couple including a rotating cylinder, means for feeding sheets to the couple including registration stop means against which a sheet is preliminarily fed, feed rollers for advancing the sheet from the stop means to the printing couple, feed control means including cam means on the cylinder for moving one feed roller toward the other substantially without rotation of either feed roller and for thereafter driving one of the feed rollers to advance the sheet from the stop means to the printing couple, a sheet detector actuated by the same cam means and moved in the direction of movement of the sheet, adapted to be supported by the sheet if a sheet is present and adapted to drop through the intended plane of the sheet if the sheet is absent, and throw-out means controlled by the forward movement of the sheet detector if it has dropped through the intended plane of the sheet for separating the members of the printing couple.
